UNITED STATES PATENT OFFICE.

CHANNING WHITAKER, OF TYNGSBOROUGH, ASSIGNOR TO THE LOWELL
MACHINE SHOP, OF LOWELL, MASSACHUSETTS.

SEPARATOR MECHANISM FOR RING-SPINNING FRAMES.

SPECIFICATION forming part of Letters Patent No. 505,501, dated September 26, 1893.

Application filed April 24, 1893. Serial No. 471,898. (No model.)

To all whom it may concern:

Be it known that I, CHANNING WHITAKER, a citizen of the United States, residing at Tyngsborough, in the county of Middlesex and Commonwealth of Massachusetts, have invented certain new and useful Improvements in Separator Mechanism for Ring-Spinning Frames, of which the following is a specification, reference being had therein to the accompanying drawings.

In ring-spinning frames at present in use various devices are employed adjacent to the spindles thereof for the purpose of restricting the ballooning of the yarns which are being spun and wound upon the spindles, and also for preventing the yarns of the adjacent spindles from interfering with one another. In the case of some of the earlier applications of such devices to ring-spinning frames, the separators were rigidly attached to the ring-rail between the rings, or were elsewhere similarly mounted in positions closely adjacent to the spindles. This proved inconvenient and disadvantageous, for it rendered difficult the cleaning of the ring-rail and rings, promoted the accumulation of fly and dirt, and interfered with the doffing of the bobbins or cops from the spindles. Afterward, the separators were applied to a horizontal rail, shaft, or rod, pivotally mounted in bearings projecting from the rear side of the ring-rail, and capable of being turned in such bearings to throw the separators upward and backward away from the spindles and the upper surface of the ring-rail. This obviated some of the disadvantages of the arrangement just mentioned, but still, as also occurred in the case of the latter, the weight of the parts which were added to and carried by the ring-rail tended to bend or spring the latter and otherwise to interfere with the satisfactory operation of the machine. Later, by mounting the horizontal separator-rail, shaft, or rod, in bearings carried by the machine framing, the ring-rail has been in part relieved of the strain thus imposed upon it, the separators being caused to project across the ring-rail as previously, and being struck by the latter in its upward movement so as to be caused to rock vertically during the continued rise of the said rail, the weight of the separators op-

erating to return them to their original position during the descent of the ring-rail. While this arrangement has proved in practice to be superior to the earlier ones, it still causes the weight of the separators, or a part thereof when a counterbalancing weight is applied to the separator-rail, shaft, or rod, to be imposed upon and sustained by the ring-rail at certain times in the movement of the latter, and otherwise is found to fail to answer completely practical requirements. Various subsequent improvements of considerable merit have been devised, the principal ones having as their main objects to sustain the separators and actuate them by suitable operative connections without any strain or weight being imposed upon the ring-rail. The best, according to my opinion, among these improved separator-mechanisms, are those of the class in which the horizontal shaft, rod, or rail carrying the separators is supported at the upper ends of vertical rods, known as separator-rods, having vertical movements transmitted to them from the cross-shaft arms which actuate the lifting-rods for the ring-rail, the separator-rail and ring-rail being thereby caused to move in unison, but the traverse of the separator-rail being of less extent than that of the ring-rail.

My invention is designed as an improvement upon separator mechanisms of this class, and has for its main object to provide a separator mechanism which shall be durable, respond to all the requirements of practical use, be of the simplest possible character and construction, consume the least possible amount of power, exert the least possible stress upon those parts of the ring frame from which the necessary motion is derived, and permit the use of the widest separator-blade which can be received between the top of the ring-rail and the bottom of the thread-guide.

Other objects of my invention are to provide guiding and directing devices of novel and improved character for determining the path of movement of the separator-rail; to render it unnecessary to make any vertical change or shift of the traverse of the separator-rail and separators such as heretofore it has been found necessary to make in the case of separator-mechanisms of this class in order

to compensate for changes in the length of the traverse of the ring-rail; and to provide simple and practical means for mounting the separator-rail in a manner which not only 5 will enable the separators to be moved or turned away from between the spindles when desired, but will permit the separator-rail to be taken from its movable supports at any time, and removed from the machine, without 10 it being necessary first to turn the separators into their inoperative position in order to unlock the rail from the supports.

Further objects of the invention will be developed in the course of the following description.

15 My invention consists in certain novel, useful, and improved combinations of parts, and features of construction and arrangement, all as will be clearly indicated hereinafter, and 20 it first will be fully described with reference to the accompanying drawings, and then will be particularly pointed out and clearly defined in the claims which are appended at the close of this specification and which form a 25 part hereof.

In the drawings, Figure 1 is a view in front elevation of a ring-frame having applied thereto an embodiment of my invention in its most complete form. Fig. 2 is a view in transverse section on the dotted line 2—2 of Fig. 30 1. Fig. 3, Sheet 2, is a view in front elevation showing certain of the parts of a ring-frame, with a simplified construction of mechanism applied thereto. Fig. 4, Sheet 2, is a 35 view in vertical transverse section on the dotted line 4—4 in Fig. 3. Fig. 5, Sheet 2, is a view in plan, parts being broken away and in section, of portion of a cross-shaft, its arm, and portions of the lifting-rod and vibratile connecting-rod hereinafter described. 40 Fig. 6, Sheet 2, is a view in vertical section on the dotted line 6—6 in Fig. 3. Fig. 7, Sheet 3, is a view in vertical section on the line 7—7 in Fig. 8. Fig. 8, Sheet 3, is a detail view in 45 rear elevation showing part of a cross-shaft arm, the vibratile connecting-rod actuated thereby, the guide for the said rod, the stand carrying said guide, the supports for said stand, and part of a separator-rail. Fig. 9, 50 Sheet 10, is a view in plan of the said guide. Fig. 10, Sheet 10, is a view in vertical section on the line 10—10 of Fig. 9, it showing part 55 of the stand. Fig. 11, Sheet 10, is a view in side elevation of the parts that are represented in Fig. 9. Fig. 12, Sheet 10, is a view in plan of the upper end of the separator-stand. Fig. 13, Sheet 3, is a view in elevation illustrating a modified stand and guide. Fig. 14, Sheet 60 3, is a view in plan of the parts shown in Fig. 13, with the exception of the vibratile connecting-rod, which is in horizontal section. Fig. 15, Sheet 3, is a view in vertical section on line 15—15 of Fig. 14. Figs. 16 and 17, Sheet 3, are views in vertical section showing 65 modified forms of guide. Figs. 18, 18^a and 18^b, Sheet 4, are views illustrating a still further modification in the manner of support-

ing the guide. Figs. 19 to 34, inclusive, Sheets 5, 6 and 7, are views, of character hereinafter set forth, showing modifications hereinafter 70 described. Fig. 35, Sheet 8, is a view in vertical section on line 35—35 of Fig. 1. Figs. 35^a, 35^b, 35^c and 35^d, Sheet 8, show details hereinafter described. Fig. 36, Sheet 8, is a view in vertical section on line 36—36 of Fig. 75 1. Figs. 36^a, 36^b, and 37 to 44, inclusive, Sheets 5 and 6, are views, of character hereinafter specified, showing modifications hereinafter described. Figs. 45 to 48, inclusive, Sheet 9, are views showing the manner of supporting the cross-shafts. Figs. 49 to 59, inclusive, Sheet 10, are views of character hereinafter specified illustrating the details of the means whereby the separator-rails are supported by the upper ends of the vibratile connecting-rods. Figs. 60 and 61, Sheet 3, are views illustrating a modified form of the pivotal connection between the cross-shaft arm and the vibratile connecting-rod. Fig. 62, Sheet 3, represents a modification of the parts 90 shown in Figs. 60 and 61. Fig. 63, Sheet 11, is a diagram, hereinafter referred to.

In Figs. 1 to 4, 1, 1, are the roller-beams, 2, 2, the thread-boards hinged thereto, as usual, 3, 3, the finger-boards hinged as usual to the thread-boards, 4, 4, the yarn-guides secured to the finger-boards, 5, 5, the yarns passing from the yarn-guides 4, 4, to the bobbins 6, 6, through the travelers 7, 7, on the rings 8, 8, supported by the ring-rails 9, 9. 10, 10, are 100 the spindles on which the bobbins are mounted, 11, 11, the spindle-rails, 12, 12, the lower or guide-rails, 13, 13, the lifting-rods for the ring-rails, and 14, 14, the shoes at the lower ends of the said rods. 15 (see particularly 105 Figs. 5 and 6) is the stud upon which, or upon the roller 151 carried thereby, the undersurface of each of the said shoes rests, and 152 is the flat-headed screw which holds the roller in place upon the stud 15 when the said roller 110 is employed, the threaded part of the said screw being caused to enter a threaded hole in the end of the stud. 16, 16, are the cross-shaft arms by which the studs 15, or studs 15 and rollers 151, are carried, and 17 is the 115 transverse slot in the free end of each of the said arms in which the corresponding stud is mounted adjustably. 171 is a collar on each stud which takes bearing against one side of the cross-shaft arm 16 to which the same is 120 applied. 172 is a nut on the threaded end of the stud on the side opposite to that on which the collar 171 is located, and 173 is a washer which is placed between the said nut and the adjacent side of the arm. 18, 18, are 125 the cross-shafts provided with the said arms 16, 16, and 19, 19, are the brackets containing the bearings for the cross-shafts, the cross-shafts being caused to rock by well-known means for the purpose of moving the ring-rails up and down. At 20 are shown the separators.

All of the foregoing parts may be of any usual or preferred construction.

At 21, 21, are shown the separator-rails on which the separators are mounted. For the sake of lightness, I preferably make the separator-rails 21 tubular or hollow.

5 Heretofore, in constructions of separator-mechanisms of the class on which the present invention is an improvement, the horizontal separator-rail has been attached to or mounted in bearings upon the tops of vertical separator-rods, and it has been the practice to mount the separator-rods, for the purpose of defining their path of movement, and that of the separator-rail and separators, in an upright position in fixed guides, by which latter they are compelled to move strictly in a straight line in a vertical direction and are prevented from deviating or vibrating laterally, as otherwise they might be caused to do by the action of the swinging cross-shaft 20 arms from which they are operated, inasmuch as the said arms swing through arcs of movement having horizontal components, as will be understood from an inspection of Fig. 63. Frequently, in consequence of the fact that 25 the arcs of movement of the said cross-shaft arms have each a horizontal component as just mentioned, it has been deemed necessary or expedient, particularly in some constructions wherein the actuating connections between the cross-shaft arms and the separator-rods are offset laterally with respect to the axes of the separator-rods, to employ special provisions for preventing the separator-rods from being caused to twist or turn upon their 30 vertical axes within the guides as the cross-shaft arms rise and fall through their said arcs of movement. The said horizontal component, moreover, necessitates making the engagement or connection of the cross-shaft 35 arms with the guided upright separator-rods in some special manner or by some special means which will not interfere with the horizontal movement of the actuating parts of the cross-shaft arms relatively to the separator-rods.

45 A prominent and characteristic feature of my improved separator-mechanism as hereinafter described is that it contains no separator-rods or slide-rods held by fixed guides in a definite vertical position and prevented thereby from lateral movement or vibration. Instead of employing such separator-rods or guides, I employ vibratile rods on the order of simple connecting-rods or pitmen, each of 50 which at its upper end is formed or provided with a bearing that suitably receives the journal of the corresponding separator-rail, while at its lower end each rod is connected or engaged with the corresponding cross-shaft arm, 55 the rod being free to swing or vibrate laterally in a vertical plane which is parallel with the vertical plane in which the cross-shaft arm moves, as the said cross-shaft arm swings up and down through its arc of movement in 60 actuating the ring-rail.

65 In combination with the vibratile connecting-rods I use directive devices or guides of

simple construction for holding the separator-rail to its proper path of movement, as it rises and falls in unison with the ring-rail. 70

As clearly will be made to appear presently, I simplify greatly the construction of the separator-mechanism. The employment of the kind of guides heretofore in use, and the fitting and adjusting of such guides are 75 avoided. Inexpensive forms of guides or directive devices are used. More direct and much simpler connections with the cross-shaft arms may be made than heretofore, and, inasmuch as the vibratile connecting-rods 80 have no tendency to twist or turn on their vertical axes, the employment of provisions to prevent such twisting or turning is unnecessary, and is dispensed with.

The vibratile supporting and connecting-rods aforesaid are shown at 22 in various figures of the drawings. They are formed or provided at their upper ends with bearings 221 for the reception of the journals or pivots of the separator-rails, (see Figs. 49 to 52, 90 inclusive, 54 and 56,) and at their lower ends are pivotally engaged or connected with the cross-shaft arms 16, 16.

In Figs. 3, 4, and 8, I have shown, in combination with certain of the parts at one side of 95 a ring-spinning frame, a preferred simple embodiment of the vibratile supporting and connecting-rods and the directive device or guide for determining the path of movement of the separator-rail as it rises and falls. In these 100 figures the rod 22 is formed at its lower end with an eye 23 which is entered by a stud or pin 24 formed or otherwise provided on the side of the cross-shaft arm 16, see Fig. 7, the said eye being kept on the said stud or pin 105 by means of a split pin 25 which is passed through the end of the stud or pin 24 outside of the eye 23. The stud or pin 24 is located at a point intermediate the axis on which the cross-shaft 18 turns and the point at which 110 motion is transmitted to the lifting-rod 13. Through the described pivotal connection of the vibratile rod 22 with the cross-shaft arm 16, motion is communicated from the said arm to the rod, and to the separator-rail and separators sustained thereby. In consequence of 115 connecting the rod 22 with the cross-shaft arm 16 at a point between the axis on which the arm rocks and the point on the arm at which motion is communicated to the lifting-rod 13, the 120 movement communicated to the rod 22, separator-rail, and separators, while occasioned simultaneously with that communicated to the lifting-rod, ring-rail and rings, is less in extent than the latter movement, and thus the 125 extent of the traverse of the separator-rail and separators is made less than that of the ring-rail and rings. The bearing 221 provided at the upper end of rod 22 for the reception of the journal or pivot of the separator-rail 21 is formed as an open or half bearing in which the said journal or pivot rests 130 and in which the said journal or pivot is held by the gravity of the separator-rail and the

parts carried thereby. It is intended that the rod 22 shall be left capable of swinging laterally without obstruction as its lower end passes from one point to another of the arc 5 in which the stud or pin 24 travels in the rise and fall of the cross-shaft arm 16. See Fig. 63. All that I contemplate employing in the shape of a guide in connection with the vibratile rod 22, or with the separator-rail 21, is 10 a directive device or devices for one or both of them which shall hold the separator-rail and its separators to a proper path of movement as they rise and fall, and without interference with the lateral vibration of the 15 rod 22.

In Figs. 3, 4, and 8, I use merely a stationary eye or steadier-guide 26, in the shape of a ring or short bearing, which surrounds the rod 22 at a point that is located as near to 20 the separator-rail as is convenient and practicable in view of the traversing movement which is communicated to the separator-rail. This eye or guide 26 is employed simply for the purpose of preventing the separator-rail 25 and separator from falling toward the front, rear, or either end of the ring-spinning frame. It is located at the upper end of a stand 27, which latter may be secured to any suitable part or parts of the machine framing. Preferably the said stand is held to the rails 11 and 12 by screws 28, 28, passing through vertically elongated slots 29, 29, in the stand and into the said rails. The form and construction of the stand 27 are shown most clearly 30 in Fig. 8. The object of the slots 29, 29, is to permit the stand and guide to be adjusted vertically as occasion may require, as, for instance, when the rails 11 and 12 have been adjusted higher or lower in the frame to provide 35 for changes in the length of the bobbins 6. As above indicated, the guide 26 is placed as near to the separator-rail as is practicable in view of the vertical traverse movement which is communicated to the separator-rail. 40 Between the said guide and the point at which the vibratile rod 22 is connected to the cross-shaft arm 16 there is nothing to interfere with the lateral vibrations of the rod 22 which will occur as the cross-shaft arm swings in a vertical plane. By preference, the hole 30 in 45 the guide 26 through which the rod 22 passes, see Fig. 10, Sheet 10, and Fig. 15, Sheet 3, is made of substantially the same diameter as the said rod at the top of the hole, but just 50 enough larger to permit the rod to slide therein freely, and of a slightly greater diameter at the bottom than at the top, or, in other words, slightly flaring toward the bottom, so as to permit free oscillation or vibration of 55 the rod to the necessary extent about the center of the hole at the top of the box. The flare, or difference between the diameter of the hole 30 at its top and the diameter of the 60 said hole at its bottom is shown exaggerated in Figs. 10 and 15. Inasmuch as the rod 22 is long, the vibratory movement of the said rod at the point where it passes through the

guide 26 is so slight that the diameter of the hole 30 in the latter does not need to be very much larger at the bottom thereof than it is at the top thereof. Sometimes I make the smallest part 301 of the hole 30 at a short distance below the top of the hole, as indicated in Fig. 16, Sheet 3, and sometimes I may omit altogether to taper the hole and may make it 75 cylindrical, as in Fig. 17, Sheet 3.

To facilitate the application of the rod 22 to the guide 26, and the removal of the said rod therefrom, the guide preferably is made of a two-part separable construction as represented in Figs. 8 to 15. In these figures, the cap 261 is secured to the main or other portion 262 of the guide by screws 263, 263. The guide 26 may be connected with the stand 27 by forming the entire guide, when it is not 80 split or divided, integral with the stand, or, by forming the main portion or body of the two-part guide integral with the stand in the manner indicated in Figs. 13, 14, and 15, Sheet 3. Preferably, however, the guide is made 85 separate from the stand and secured thereto by suitable means. This enables me to provide for adjusting the said guide horizontally upon the said stand in a manner which will bring the separator-rail and the separators 90 into exactly the position which they should occupy relatively to the spindles and other adjacent parts. Such a construction is represented in Figs. 8 to 12. These figures show the top of the stand formed with a flat horizontal surface 271, and with lateral lugs 272, 272, through which are made vertical holes 273, 273. The guide 26 is placed on the said surface 271, it being formed with lateral lugs 264, 264, through which are made vertical 95 holes 265, 265. Through the holes 273, 265, are passed bolts 274, 274, which receive on their threaded ends nuts 275, 275. By means of the said bolts and nuts the guide is held to the stand. The holes 273, 265, are larger 100 in diameter than the diameter of the bolts 274, 274, and hence when the nuts are turned so as to loosen the parts the guide may be adjusted universally in a horizontal plane. As will be understood, adjustment horizontally 105 of the guide will carry with the latter the upper end of the rod 22, and therefore will adjust the separator-rail and separators so as to cause them to occupy the desired positions during their working.

In Figs. 18, 18^a, and 18^b, Sheet 4, I have shown another means of supporting the directive guide, 26, in suitable position, and with capacity for being given any vertical or horizontal adjustment which may be required for 115 the purpose of bringing it into the proper and desired position. Fig. 18 is a view in front elevation showing the guide, 26, and its supporting stand, and portions of the frame-work of the ring-frame. Fig. 18^a is a view showing the guide and stand in side elevation, and the said portions of the frame-work in vertical section. Fig. 18^b is a view in section on the dotted line 18^b—18^b of Fig. 18^a. In these fig-

ures the guide is shown as being carried by the stand 2711, the lower part of which has a vertical flange or foot, 2712, provided with a vertical slot, 2713, through which passes a bolt, 2714, which secures it to the rear side of the spindle-rail. The slot, 2713, permits the spindle-rail to be adjusted up and down, as the lengths of the bobbins to be used in the ring-frame may require, without the position of the stand being interfered with. The body of said stand is curved at the lower part thereof so as to throw the upper portion of the said stand rearwardly, and cause it to occupy, when in place, a position beneath the roller-beam 1. 15 The upper end of the stand is connected with the vertical flange of the roller beam, 1, by a bolt, 2715, passing through the said vertical flange and the said upper end, and receiving on its threaded end a nut, 2716. To the body 20 of the stand is applied, at a suitable height thereon, the horizontally projecting bracket, 2717, the same being shaped, as shown, at its rear end to fit upon and between the side portions of the open portion of the said body, 25 and being held to the said body by means of a bolt, 2718, passing through a vertical part of the bracket, and also through a retaining plate, 2728, which is similarly fitted to the rear side of the body portion, the said bolt 30 having fitted upon its threaded end the nut, 2719. The open construction of the body of the stand, and the securing means described, enable the bracket to be adjusted vertically as may be required, either in setting up and 35 fitting together the parts, or in adapting them to the requirements of practical use. The forward part of the bracket is provided with a ledge on which the guide is fitted with capacity for adjustment in a horizontal plane. 40 The form and construction of the guide, and the manner of applying and securing it to the bracket, are, or may be, substantially as shown in Figs. 9 to 12, and hereinbefore described.

45 To prevent the separator-rail from moving endwise through the bearings 221, 221, on the rods 22, 22, in the construction which is represented in Figs. 3, 4, and 8, I form or provide shoulders or collars 211, 212, Fig. 8, on 50 the separator-rail to come in contact with the bearing portions, 221, at the upper ends of rods 22, 22, on opposite sides of the said bearings. Such shoulders or collars may be located on both sides of a single bearing for 55 each separator-rail, or on opposite sides of each of two or more of the bearings for the same separator-rail, as will be obvious, or one of the same may be located at one side of one bearing for the rail and another at the opposite side of another bearing therefor, as will be obvious without further explanation.

In Fig. 8, the collars 211, 212, are slipped on the separator-rail 21, and clamped in proper position thereon by screws 213, 213. 60 Collar 212, in Fig. 8, is constituted by the hub of one of the separators 20. By preference, the bearing 221 is made, at mid-length, as at

232, Fig. 51, Sheet 10, a trifle higher than it is at each side of the middle, thus producing a slightly raised ridge on which the separator-rail journal or pivot bears, and which ridge accommodates the vibratory movement of the rod 22. 70

In Fig. 51, the height of the ridge is exaggerated in order that it may be more certain to attract the attention of the reader to the drawing. However, this ridge is not an indispensable feature of my invention, inasmuch as the oscillation of the upper end of the separator-rod is very slight, and this feature may be omitted, when desired. 75

During the working of the ring-spinning frame, the operation of the described mechanism is as follows:—When the cross-shaft arm swings up and down through its path of motion, the pivotal connection of the rod 22 therewith will cause the said rod, and the separator-rail and separators, to move up and down, simultaneously with the lifting-rod, ring-rail, and rings, but at a lower rate of speed than the latter and through a traverse of less extent. In consequence of having the lower end of the rod 22 pivoted to the cross-shaft arm, the axis of such rod will not remain in one and the same vertical line as the rod moves up and down. The center of the eye at the lower end of the rod will move in the arc of a circle about the axis of the cross-shaft arm, and, this movement having a horizontal component, as is indicated in Fig. 63, the rod will oscillate, or swing back and forth laterally, in a vertical plane parallel with that in which the cross-shaft arm swings. Within the guide 26, the axes of the guide and of the rod will be caused to remain substantially coincident, so that the longitudinal axis of the rod, in the lateral oscillation of the rod, will swing through a slight angle about a horizontal axis passing through the center of the hole at the height at which the exterior 105 of the rod takes bearing on the interior of the guide in the oscillation or vibration of the rod. The guide 26 will be adjusted laterally to such a position that when the separator-blades are in their lowest position, at which 110 time they require to be located most precisely between the spindles, the planes passing vertically through the separator-blades at the middle of the thickness of each blade will be located midway between the axes of the spindles. With this adjustment secured, as the separator-blades pass to the upper portion of their traverse the said middle planes of the separator-blades will become shifted very slightly 115 to one side of positions midway between the 120 axes of the spindles. This results from the horizontal component of the movement of the stud or pin 24, as the cross-shaft arm 16 rises and lifts the connecting-rod, the separator-rail, and the separators. However, inasmuch as the portion of the rod that is below the line of bearing in the guide 26, see line $x-y$ of Fig. 63, is many times the length of the portion 125 that is above the said line, the lateral move-

130

ment of the upper end of the rod 22, and the resulting departure or deviation of the middle planes of the separator-blades from positions midway between the axes of the spindles, become too slight to be of any practical importance, particularly since this departure or deviation, which in practice I have found not to exceed one twenty-fifth of an inch in a properly proportioned and adjusted mechanism, is greatest when the separator-blades are near the upper portion of their traverse, at which time the ballooning is too slight to make it necessary that separators shall be used.

15 The directive means, whereby the separator-rail is kept in place and its path of motion determined, may be constructed and applied in various ways different from that which has been presented hereinbefore.

20 Fig. 19, Sheet 5, is a view, partly in horizontal section on the plane indicated by the dotted line 19—19 in Fig. 20, of a modification in which each of the ends of the separator-rail enters between the ribs 31, 31, on a

25 plate 311 that is shown most clearly in Fig. 20, which latter is a view in vertical section on line 20—20 of Fig. 19. The plates 311 are secured to suitable portions 441, 441, of the machine-framing by bolts 313, 313, that pass

30 through lugs 314, 314, on the said plates, and also through the portions 441, 441, of the machine-framing, and receive nuts 315, 315, on their threaded ends outside the said portions 441, 441, of the machine-framing. The 35 ribs 31, 31, keep the separator-rail from falling backward or forward in the machine, and the contact of the extreme ends of the separator-rail with the vertical faces of the plates between the ribs prevents the separator-rail 40 from shifting endwise.

In Fig. 21 I have shown in end elevation, and in Fig. 22 in side elevation with a roller-beam in vertical section, a modification in which a vertically-slotted bracket 32 is attached to the roller-beam 1 at an intermediate point in the length of the latter by bolts 321, 321, passing through lateral ears 322, 322, on the bracket and also through the vertical flange of the roller-beam, the said bolts receiving nuts 324, 324, on the threaded ends thereof at the rear of the said vertical flange. The slot 323 in the said bracket is open at the top to permit the separator-rail 21 to be dropped into the slot from above. The front and rear walls of the slot prevent the separator-rail from moving toward the front or the rear in the ring-frame, and the separator-rail is prevented from moving endwise by means of the collars 325, 325, that are mounted

60 thereon on opposite sides of the bracket 32 and are held in place thereon by clamping screws 326, 326, which pass through the collars and take bearing by their ends against the surface of the separator-rail. In Fig. 23, 65 which is a view corresponding in character with Fig. 22, a somewhat similar bracket 33 is shown in side elevation, it having the slot

open at the lower end of the bracket so as to necessitate the introduction of the separator-rail into the said slot from below. Along the front of the roller-beam a sufficient number of the brackets shown in Figs. 21 to 23 will be employed to guard against horizontal springing or vibration of the separator-rail. The collars on the separator-rail, however, actually need be used in connection with one, only, of the said brackets, for this will be sufficient to keep the separator rail from moving endwise.

Figs. 24 and 25 are, respectively, a front elevation and a partly sectional side elevation, showing a bracket 34 held to the roller-beam 1 by bolts 341, 341, and nuts 342, 342, the said bracket having a forwardly projecting arm 343 from which depends a vertical 85 guide-rod 344. On this guide-rod 344 fits a sliding collar 345 that is connected with the separator-rail 21. The guide-rod 344 and collar 345 constitute the only directive means necessary to be employed for the purpose of holding the separator-rail to its proper path of movement.

Fig. 24^a is a plan of the device represented in elevation in Figs. 24 and 25, and Fig. 24^b is a sectional plan taken at the line 24^b—24^b, 95 of Fig. 24.

Figs. 26 and 27 are views similar to Figs. 24 and 25 in character, showing a similar vertical guide-rod 35 projecting upwardly from a horizontal arm 351 on a bracket 352 that is held by bolts 353 to a stationary rail, the rail shown in the said figures being the spindle-rail 11. The guide-rod 35 has applied thereto the collar 345 that is connected with the separator-rail 21.

Figs. 28 and 29, Sheet 6, are similar views which show a modification in which a guide-rod 36 projects upwardly from a bracket 361 on the lifting-rod 13, the said bracket being secured in desired position on the lifting-rod 110 by means of a clamping screw 362, and the guide-rod 36 having applied thereto the collar 345 that is connected with the separator-rail 21. In this modification the extent of the movement of the collar 345 upon the guide-rod is much less than in Figs. 24, 25, 26, and 27, in consequence of the fact that the collar and guide-rod move simultaneously in the same directions during the rise and fall of the separator-rail and ring-rail in the operation of the machine. The movement of the collar upon the guide-rod in Figs. 28 and 29 is equal in extent to the difference between the vertical traverse of the lifting-rod 13 and ring-rail and that of the rod 22 and separator-rail.

In the case of the modifications shown in Figs. 24 to 29 as many of the guiding and restraining devices will be employed on one side of a ring-frame as it may be necessary to use in order to prevent the horizontal springing or vibration of the separator-rail.

The directive devices hereinbefore described may be variously applied to one and

the same machine, as may be deemed advisable, more than one form or modification thereof being employed in a single ring-frame if considered advisable and necessary. However, although in practice a rod 22 will be employed in connection with probably each cross-shaft arm 16 in a ring-frame, the number of directive devices employed in connection with each separator-rail will be only such as is required for the purposes of keeping the separator-rail steady, or without horizontal springing or vibration, and of causing the same to move in a proper path.

The blades of all the separators carried by a separator-rail project to one side of the separator-rail. This occasions a quite considerable preponderance of weight on such side, and tends to bear or tilt the separator-rail and its rods 22 outwardly from the machine, creating pressure and friction on the sides of the restraining and directing guides when the latter are on the order of those hereinbefore presented. This pressure and friction are prevented from occurring in the embodiment of my invention illustrated in Fig. 30, Sheet 7, which is a view in vertical section showing certain features of my invention applied to certain parts of a ring-frame, and in Fig. 31, which is a plan view of the parts shown in Fig. 30, with the roller-beams shown in dotted lines. In these figures, a clamp 37, fixed to each rod 22 at, or very near to, the upper end thereof, has connected thereto, one end of a radius-rod 372, which latter has its other end jointed to an arm or bracket 376 fixed, by a bolt 374 and nut 375, to the roller-beam 1 on the opposite side of the machine. This radius-rod 372 may be a slender wire or tie-rod, in which case it wholly overcomes the tendency of the preponderating weight to tilt the separator-rail and its rod, 22, outwardly from the machine, but I prefer to use a stiff rod capable of performing the part of a strut as well as that of a tie-rod, in which case it prevents the separator-rail from having any undesired movement in either direction transversely of the machine. The distance from the separator-rail 21 and rod 22, on one side of the ring-frame, to the point of connection of the corresponding radius-rod with the bracket 376 on the roller-beam 1, on the other side of the ring-frame, is so great that the arc in which the outer end of the radius-rod moves as rod 22 rises and falls has a very slight curvature. The curvature, in fact, is so slight that the backward and forward movement of the separator-rail and separators, resulting therefrom, is not noticeable. Moreover, such movement is of no consequence, for it is in such direction that it does not lessen the efficiency of the separators, or interfere with the attainment of satisfactory results. When these radius-rods are used, it is convenient to hold the separator-rail from movement endwise by causing its ends to slide in contact with smooth surfaces 38,

either on the end frames of the machine or on other parts suitably provided for the purpose. See the view in horizontal section presented in Fig. 32, Sheet 7. Other forms of guides or restraining devices may be used, however, to prevent endwise movement of the separator-rails.

It is not necessary that all of the guiding and restraining devices employed in connection with the separator-rail on one side of the ring-frame should be duplicated for use in connection with the separator-rail on the other side. I contemplate connecting the moving parts of the separator-mechanism on one side of the ring-frame to the moving parts thereof on the other side of the ring-frame, in such manner that the duplication of such devices may be made unnecessary in whole or in part. Thus, in Fig. 33, Sheet 7, which is a view in vertical section of one modification of my invention, and in Fig. 34, which is a view in plan of the main features thereof, the roller-beams being omitted, only one radius-rod 372 is used, it connecting with a rod 22 pertaining to the separator-rail 21 on one side of the ring-frame, only. The said rod 22 is connected with the corresponding rod 22 of the separator-rail on the other side of the ring-frame by a tie-rod, or cross-rod, 39, each end of the latter being connected to a clamp 37 on the corresponding rod 22. By this means, the tendency of the second separator-rail to fall outward in consequence of the preponderating weight of the projecting blades of its separators is overcome, and, whenever the cross-rod 39, is, as is sometimes the case, made sufficiently stiff to act as a strut as well as a tie, the separator-rail is prevented by it from moving toward the middle of the machine. In addition, a very important result is secured by the use of the cross-rod 39; it compels the force which acts to tilt each separator-rail outwardly on its side of the ring-frame to act, in the cross-rod 39, in opposition to the corresponding force which acts to tilt the other separator-rail outwardly on the other side of the ring-frame. The two forces balance each other within the cross-rod 39, and thus practically are neutralized, so that there is no longer any great tendency of either of the separator-rails to move outwardly in consequence of the preponderating weight of its separator-blades. The use of the cross-rod 39 is of particular benefit in those constructions in which are employed guides on the order of the various forms of guides that are shown in Figs. 3, 4, and 8 to 29, for, by relieving the said guides from the outwardly exerted pressure due to the weight of the separator-rails and the moving parts connected therewith, the friction, and also the wear of the said guides, are diminished.

Fig. 35, Sheet 8, is a view in vertical section on the line 35—35 in Fig. 1, illustrating the use of a tie-rod or cross-rod 39 in connection with the form of guide illustrated in Figs. 3, 4, and 8 to 17.

Fig. 36, Sheet 8, is a view in vertical section on line 36—36 in Fig. 1, and illustrates the use of the tie-rod, or cross-rod, for uniting and balancing purposes in connection with a pair of opposite rods 22 which, at the point in the length of the ring-frame at which the section is taken, are without any restraining or holding devices applied thereto other than the tie-rod or cross-rod, just mentioned, and 10 the separator-rails themselves, which latter have some of the described guides or restraining devices applied elsewhere.

In Figs. 33, 34, 35 and 36, the tie-rod or cross-rod is connected to the rods 22, 22, or, 15 more exactly, to clamps 37, 37, on said rods.

In Figs. 36^a and 36^b I have shown how the tie-rod or cross-rod may connect directly with the separator-rails. In these latter figures each end of the cross-rod is bent upward and 20 terminates in a socket 3921 in which is received the corresponding separator-rail. The socket 3921 is shown provided with a removable cap 3922 held in place by screws, 3923, 3923, whereby the separator-rail is retained 25 in the socket. Preferably, this socket, 3921, is applied to the corresponding separator-rail at a point alongside the socket at the upper end of a rod 22, the said sockets being held together and in place upon the separator-rail 30 by collars, 211 and 212, one of which collars may be the collar or hub of a separator, which are placed on opposite sides of the sockets and fixed to the separator-rail. In this construction the cross-rod is made sufficiently 35 stiff to enable it to serve as a strut as well as a tie-rod.

In Fig. 37, Sheet 5, which is a view in vertical section of parts of a ring-frame having applied thereto another modification of my 40 invention, and Fig. 38, Sheet 5, which is a view in horizontal section on line 38—38 in Fig. 37, I have shown a construction in which the cross-rod 39 is transformed into a light trussed frame 40, the said frame consisting 45 of the wires or rods 401, 401, which are connected at their ends with the clamps 402, 402, applied to the opposite rods 22, a middle separating piece or strut 403, and other pieces 404, 404, at points intermediate the middle and 50 the ends of the trussed frame. On opposite faces of the strut 403 are provided the pins or rollers 405, 405, which pass into slots 406, 406, that are formed in depending extensions 407, 407, of a bracket 408 held by bolts 409 55 and nuts 410 to a horizontal portion of the upper frame-work of the ring-frame. The strut 403 slides up and down between the extensions 407, 407, which latter may operate to prevent endwise movement of the separator- 60 rail, while the sides of the slots 406, 406, engage with the pins or rollers 405, 405, to prevent horizontal or lateral movement of the separator-rails. In this case, the truss 40 acts as a tie-rod, as a strut, and as a girder, resist- 65 ing the bending stress which results from the friction of the pins or rollers 405, 405, in the slots 406, 406.

From the showing in Figs. 37 and 38 will be obvious the general manner in which the cross-rod, or their equivalents, when made sufficiently stiff, may have applied thereto the guides or directive devices whereby the proper paths of movement of the separator-rails and separators may be secured.

A convenient means of connecting the ends 75 of the radius-rods and cross-rods with the rods, 22, is represented in detail in Figs. 35^a, 35^b, and 35^c on Sheet 8. Fig. 35^a is a view in horizontal section on line 35^a—35^a of Fig. 35^b. Fig. 35^b is a view in rear elevation, with the 80 cross-bar, rod, or wire in section. Fig. 35^c is a view in side elevation with one clamp-section removed. In these views I have represented the said connecting means as serving to connect one end of a tie-rod or cross-rod, 85 39, with a rod, 22. Figs. 2, 30, 31, 33, 34, 35, 36, 37, and 38 show various applications thereof. The said connecting means consists essentially of a separable clamp, 37, which engages the rod, 22, and one end of the tie-rod 90 or cross-rod. In Figs. 35^a, 35^b, and 35^c, the two halves or sections of the clamp are shown at 3711, 3711. Each of the said halves or sections is formed with a concave portion, 3712, at one end thereof, to fit upon and partly surround the rod, 22. At the other end it is formed with a lateral flange or lip, 3713, having therein a semi-cylindrical notch, 3714, formed to fit and receive part of the rod, 39. The end of the said rod is, preferably, formed with an 100 eye or loop, 3911. Holes, 3715, 3715, are formed in the halves or sections, 3711, 3711, for the reception of the stem of a bolt, 3716, which receives upon its threaded end the nut, 3717. Washers, 3718, 3718, are placed between the head of the bolt and the adjacent clamp-section, and under the nut, 3717. When the parts have been assembled, the clamp-sections, 3711, 3711, fit against opposite sides of the rod, 22, the eye or loop of the rod 110 lies between the intermediate or parallel portions, 3719, 3719, of said sections, the straight portion of said rod fits the notches, 3714, 3714, and the bolt passes through the holes, 3715, 3715, and the eye or loop of the rod, 39. By 115 turning up the nut, the halves or sections, 3711, 3711, are caused to clamp the rods 22 and 39. Preferably, the holes, 3715, 3715, are formed as elongated slots, as clearly shown, in order to permit of adjustment. This enables the distance apart of the rods, 22, 22, to be adjusted by varying the position of the bolt in the said holes or slots in one or both clamps. Sometimes, I dispense with the eye or loop, 39, and depend wholly upon the pinching of the rods 22 and 39 by means of the 120 said clamp as shown in Fig. 35^a. The resulting friction is sufficient to cause the rods 22 and 39 to remain in their proper relative positions, when the parts are proportioned with 125 this end in view.

In Fig. 39, Sheet 6, which is a view in vertical section of parts of a ring-frame having applied thereto another modification of my

invention, and Fig. 40, Sheet 6, which is a view in plan, partly in horizontal section on line 40—40 of Fig. 39, I have shown a construction in which the cross-rod, 39, has pivoted to its middle point a rocking lever, 41, having pivoted to its opposite ends the inner ends of the links 411 and 412, the former of which is pivoted at its outer end to an ear on a bracket, 413, held by bolts, 414, washers, 414', and nuts, 415, to the vertical flange of the roller-beam on one side of the ring-frame, while the outer end of the other link, 412, is pivoted to an ear on an arm or bracket, 416, held by screws, 417, to the spindle-rail, 11. In this modification, as the cross-shaft arms, 16, 16, and connecting-rods, 22, 22, rise and fall, in unison, on the opposite sides of the ring-frame, and as the cross-rod, 39, is moved up and down therewith, the said cross-rod carries with it the rocker or rocking lever, 41. The compensating effect of the oppositely acting links, 411 and 412, in tilting the rocker or rocking lever first in one direction and then in the other as the said rocker ascends and descends, will compel its pivotal point to move up and down in a straight vertical line as will be understood, and thus prevents the rods, 22, 22, and separator-rails, 21, 21, from moving to the right or left in Figs. 39 and 40.

Figs. 41 and 42, Sheet 6, show how a similar restraining device may be applied to a cross-rod, 39, for the purpose of preventing the separator-rails from moving endwise in the ring-frame. In these figures, the rocker, 41, is pivoted between ears projecting from a collar 393 mounted on the cross-rod, 39, and secured in place thereon by a clamping screw 394.

In constructions employing a cross-rod, 39, which has the functions of a tie-rod, of a strut, and of a girder, and which is rigidly connected with the upper ends of the rods, 22, 22, a second cross-rod, 42, Fig. 39, may be similarly connected with each pair of opposite rods, 22, 22, near the lower ends thereof and adjacent to the points at which the rods, 22, 22, are connected with the cross-shaft arms, 16, 16. The two rods, 22, 22, which are thus rigidly connected with each other and with an upper cross-rod, 39, and a lower cross-rod, 42, become parts of a light rectangular frame of considerable stiffness and stability which rises and falls as the cross-shaft arms swing up and down.

Each cross-rod, 39 and 42, may be in two parts or lengths which are united by a turn-buckle, consisting of a swivel-nut, 421, whereby the length of each tie-rod may be adjusted, lock-nuts, 422, 422, being located at the ends of the swivel-nuts, 421, to preserve the adjustment. I consider it better, however, to adjust the distances apart of the rods, 22, 22, at their upper and lower ends, and the angles which the rods, 22, 22, make with the cross-bars, 39 and 42, by means of the sockets, 43, 43, 43, 43, shown in Figs. 39, 43, and 44, Sheet 6.

In Fig. 43, I have shown by a view in vertical section one of these sockets, 43, 43, 43, 43, and in Fig. 44, I have shown in plan the parts represented in Fig. 43. Each socket, 43, has a vertical portion, 431, having a laterally widened hole, 4312, vertically therethrough, through which hole the rod, 22, passes, and a laterally projecting nipple, 432, 75 in which is secured the end of the cross-bar, rod, or wire, 39 or 42. Adjusting-screws, 433, 433, 433, pass through the wall of the portion, 431, and take bearing against the surface of the rod, 22, thereby securing the socket, 43, 80 in place on the rod, 22. Two of the adjusting-screws, 433, 433, are situated at the opposite ends of the socket, and on one side of the latter, while the third adjusting-screw, 433, is situated at an intermediate point, and on the 85 opposite side of the socket. By means of these oppositely-acting adjusting-screws, a delicate adjustment of the rods, 22, 22, laterally, and of the angles which they make with the cross-rods, 39 and 42, may be secured. 90

When an ordinary ring-spinning frame having the separator-mechanism operated from the cross-shaft arm is altered so as to adapt it to the use of bobbins of a length different from those which have been used 95 thereon, a compensating adjustment in the separator-mechanism is required, in consequence of the change that is made in the height of the cross-shaft. This change is incident to the adjustment, vertically, of the 100 spindle-rail, which is effected for the purpose of bringing the tips of the bobbins at the requisite distance from the thread-guides, it being customary to adjust each spindle-rail, 11, of a ring-spinning frame, at the time of 105 each change in the length of the bobbins, to such a height in the frame as that when the bobbins, 6, 6, are applied to the spindles, 10, 10, the tips of the bobbins shall be at the same fixed distance below the thread-guides, 110 4, 4, regardless of the length of the bobbins.

Heretofore it has been usual to have the spindle-rail, 11, and guide-rail, 12, connected together by intermediate vertical pieces, the two rails 11 and 12, with the intermediate 115 connecting pieces making up what is ordinarily known as the ladder, and it also has been usual to hang the cross-shaft to the lower side of the guide-rail, 12, by means of the bracket or hanger, 19, as shown in Figs. 120 3 and 4, Sheet 2, the whole of the ladder being moved upward when shorter bobbins are substituted for longer ones, or downward when longer bobbins are substituted for shorter ones, and the ladder carrying the 125 cross-shaft with it in each case.

It is customary to have the mechanism which actuates the cross-shaft and its arm to raise and lower the ring-rail so arranged as that the upper limit of the movement of the 130 stud, 15, or of the stud and its roller, 151, shall be at the same fixed point, and hence that the upper limit of the traverse of the ring-rail shall be at the same fixed distance

below the thread-guides for all lengths of bobbins, the change in the traverse required to suit a new length of bobbins being secured by adjustment of the coppering mechanism in 5 such manner as to raise or lower the lower limit of the traverse of the ring-rail to the extent that may be necessary.

Inasmuch as it has been found in practice that the nearer the thread-guides are placed 10 to the tops of the bobbins, the better are the results secured, and whereas the parts of a ring-frame are usually arranged and operated so that the separator-blades lie in the space between the top of the ring-rail and the bottom 15 of the thread-board, when they and the ring-rail have reached, simultaneously, the upper limits of their traverses, it is customary to place the thread-guides and thread-board as near to the tops of the bobbins, and 20 as near to the upper limit of the traverse of the ring-rail, as the width of the separator-blades will permit. When the separators and the ring-rail are at the upper limits of 25 their traverses, and in correct adjustment, the separator-blades are in close proximity to the thread-board above them and to the ring-rail below them. Because of this close proximity, a mal-adjustment of the separator-mechanism, which shall alter the upper limit 30 of the traverse of the separator-blades, will lead to the striking of the thread-board by the separator-blades, if the adjustment of the upper limit of their traverse is too high, or, to the striking of the separator-blades by the 35 ring-rail, if the adjustment of the upper limit of the traverse of the blades is too low. It, therefore, will be seen that, when the frame is re-adjusted to correspond with a change in the length of the bobbins, the upper limit of 40 the traverse of the separator-rail and separators will not remain as before, for, although the stud, 15, and roller, 151, may rise to exactly the same height as before, all points on the cross-shaft arm which are intermediate 45 the said stud and the cross-shaft will have new positions at the end of the rise of the cross-shaft arm, in consequence of the change that is made in the height of the cross-shaft. Accordingly, the separator-mechanism will 50 be raised or lowered, but to a less extent than the cross-shaft, in proportion as the position of the cross-shaft is raised or lowered, and, in order to prevent the interference of the separator-blades with the thread-board, or 55 with the ring-rail, when both the separator-blades and the ring-rail are at the upper limits of their traverses, it will become necessary to make a compensating adjustment of the separator-mechanism.

50 In accordance with one part of my invention, I render it unnecessary to make any such compensating adjustment, as a sequence to the change in the length of the bobbins, for I support the brackets or hangers, 19, for 55 the cross-shafts, by a supplemental rail, 44, (see Figs. 45 and 46, Sheet 9, which are detail views in front elevation, and in vertical sec-

tion on the line 46—46 in Fig. 45, respectively.) The said supplemental rail is bolted to the end frames, 441, of the ring-frame, and, 70 also, to the intermediate frame-piece, 442, at a distance below the rail, 12, sufficient to permit all the usual vertical adjustments of rails 11 and 12 to be made, without any necessity for shifting the rail, 44, up and down, in consequence of such adjustments. With this arrangement, when the rails 11 and 12 are shifted vertically, it is necessary only to adjust the actuating mechanism of the cross-shafts so as to vary the lowest point of the 80 descent of the ring-rail in performing its traverse, and it is unnecessary to adjust the separator-mechanism.

For convenience in setting up or putting together the parts of the ring-frame, the slot, 85 448, which is formed in each end-frame, 441, for the passage of the bolt, 443, that holds the corresponding end of the supplemental rail, 44, to the said end-frame, (see Figs. 47 and 48,) is made vertically elongated as shown 90 in detail in Fig. 47, and a similar slot, 444, is made in rail, 44, for the passage of the bolt, 445, which holds said rail to the intermediate frame-piece, 442. These slots enable the said rail to be placed at the height required for 95 securing the proper height of the separators, &c. Each bolt, 443, receives a nut, 446, and washer, 446', on its threaded end. At their rear sides, the ladder and the rail, 44, rest 100 against a vertical rib or guide, 447, on the inner side of each end frame, as shown in detail in Figs. 45 to 48, whereby to enable them to be located properly in the ring-frame and prevent them from becoming shifted laterally 105 out of their proper positions.

In Figs. 49 to 53, Sheet 10, I have shown in detail one form of my improved means of supporting the separator-rail, 21, at the upper ends of the rods 22. Fig. 49, is a view mainly in side elevation, but with the separator-rail in transverse section, showing the upper end of a rod 22, the support applied thereto with its bearings, the separator-rail, and a stop and part of a separator that are carried by the separator-rail. Fig. 50, is a 115 view in plan of the parts that are shown in Fig. 49. Fig. 51, is a view showing in elevation part of the separator-rail and the upper end of a rod, 22, and showing, also, the support in section on a line parallel with the axis 120 of the separator-rail. Fig. 52, is a view of the support in side elevation, and Fig. 53, is a view of the same in front elevation. At 46, in these figures, is shown one of the supports for the separator-rail, it being represented as 125 formed by a socket applied to the upper end of the rod, 22, and secured thereto by a clamping screw, 461. The said support or socket is provided with the open bearing, 221, in which is received the journal of the separator-rail, 130 and into which the said journal may be dropped, readily, in assembling the parts, or from which the said journal may as readily be removed when it is desired to take the separa-

tor-rail and separators away, the said journal turning in the said bearing as the separators are shifted from their lowered or operative positions to their raised or idle positions, and vice versa. The rear wall, 462, of the open bearing is extended vertically somewhat, in order that it may serve as a guide in putting the separator-rail in place, and, also, may prevent the separator-rail from becoming dislodged, accidentally, and falling backward in the machine. The support, or socket, 46, is formed in front of the open bearing with a horizontal rest or surface, 463, which is designed to receive the impact and pressure of a stop, 464, that is carried by and moves with the separator-rail. The stop, 464, comes in contact with the rest or surface, 463, when the separators have reached their working or operative positions between the spindles, and the movement of the separators forwardly and downwardly is arrested thereby. The stop, 464, contacts with the rest or surface 463 at a point which is to the front of the separator-rail and more or less in advance of the center of gravity of the combined separator-rail and separators, and thereby the weight of the latter at the rear of the said point of contact answers the purpose of keeping the journals of the separator-rail in their bearings, and, also, it is made unnecessary to employ counterbalances to prevent the weight of the separator-blades from causing the parts to overturn.

In the embodiment of my invention, shown in Figs. 49 to 53, the stop is shown connected with the separator-rail so as to move therewith by being attached to or formed as part of the hub of one of the separators, 20. It may be connected with the separator-rail, so as to move in unison therewith, in any other manner.

The construction and arrangement of the parts in Figs. 49 to 53 are such that the open bearing and the rest are without obstruction above the same to interfere with the movement of the separator-rail and stop in being applied to the support and in being removed therefrom, and are such, also, as to permit the separator-rail to be removed directly from the support at any time, before the separators have been turned out of their operative positions, and to be taken away from the machine, without it being necessary to provide for the disengagement of the rail from the support by first turning the separators out of their operative positions, as sometimes has been necessary heretofore, in order to unlock the rail so as to enable it to be removed.

In Figs. 49 to 53, the separator-rail is round or cylindrical, and the portion thereof which enters the bearing 221 constitutes the journal for the separator-rail. In Figs. 54 to 59, Sheet 10, I have represented an embodiment of this last-described part of my invention in which the rail is rectangular in cross-section, and has the pivots or journals thereof carried by

brackets that are applied to the rear side of the rectangular rail. Fig. 54, is a view of this modification showing the separator-rail in vertical transverse section, and also showing in side elevation the upper end of a rod, 22, the support applied thereto, the bracket which is applied to the separator-rail, and part of a separator.

Fig. 55, is a view showing in plan the parts 75 that are shown in Fig. 54.

Figs. 56 and 57 are views, in side elevation, and in inverted plan, of the support.

Figs. 58 and 59 are views, in side elevation, and in plan, of the bracket. In this modification, the open bearing, 221, on the support, 46, is located somewhat farther to the rear of the horizontal rest, 463, than it is in the modification shown in Figs. 49 to 53, in order to accommodate the bracket, 465, which is applied to the rear side of the separator-rail, 21. The said bracket is shown separately, in Figs. 58 and 59. It is secured to the separator-rail, 21, by means of a screw, 466, that is passed through the countersunk hole, 467, 90 in the body or main part of the bracket, and enters the separator-rail, as shown most clearly in Figs. 54 and 55. The bracket, 465, is formed with rearwardly projecting lugs, 468, 468, having holes 469, 469, therethrough, 95 for the reception of the ends of the pin, 47, the said ends being riveted down to secure the pin in place. The said pin, 47, enters the bearing, 221, of the support, 46, and serves as the pivot or journal of the separator-rail. 100

The bracket, 465, has a forwardly projecting lug, 471, on which the lower edge of the separator-rail bears. In this construction, the blade of one of the separators, 20, is utilized as the stop which moves with the separator-rail and contacts with the rest, or surface, 463, to the front of the separator-rail and in advance of the position of the center of gravity of the combined separator-rail and separators. The details of the construction of 110 this modification vary somewhat from those of the modification which is shown in Figs. 49 to 53, but the mode of operation and results secured are substantially the same in both cases. In the case of this modification, 115 movement of the separator-rail in an endwise direction is prevented by the lugs, 468, 468, which fit on opposite sides of the portion of the support which contains the bearing 221.

The means which I have presented hereinbefore of pivotally connecting the lower end of the vibratile connecting-rod, 22, with the cross-shaft arm, 16, will be recognized from inspection of Figs. 1, 2, 3, 4, 5, 7 and 8, as being of a character to occasion positive movement of the connecting-rod, 22, in a downward direction as well as in an upward direction. The pivotal connection may be effected by various means other than that just referred to, and, if desired, the construction 130 adopted may be of a character to occasion positive movement of the rod, 22, in an upward

direction only, and the rods and parts supported thereby may be permitted to descend through the influence of gravity.

Figs. 60 and 61, Sheet 3, are views illustrating a modification embodying a construction of this latter character. Fig. 60, is a detail view, in side elevation, illustrating the said modified form of pivotal connection.

Fig. 61, is a view showing the same parts as Fig. 60, but representing them as viewed from the right-hand side in the said figure. In these figures, the foot or lower end of the rod, 22, is provided with a forwardly projecting toe, 222, having downwardly extending flanges or lips, 223, 224, at the front and rear ends thereof, respectively. In the upper edge of the cross-shaft arm, 16, is formed a notch, 161. The rounded under surface of the toe, 222, is fitted to the said notch, 161, while the flanges, 223, 224, fit against the front and rear sides of the cross-shaft arm, 16.

Fig. 62, Sheet 3, is a view corresponding with Fig. 60 of a modification of the device shown in Figs. 60 and 61, in which the flanges 223 and 224 are enlarged so as to check the rotation of the rod 22 about its vertical axis during the movements of the mechanism.

In an application for patent for improvements in separator-mechanisms for ring-spinning frames filed by me April 24, 1893, Serial No. 471,697, I have made claim to various specific features which are contained in the particular embodiments of my invention that are presented in Figs. 39, 40, 43, and 44, these features being first the frame sustaining the separator-rails on the opposite sides of a ring-frame and having actuating connections, such, for instance, as pivotal connections with the cross-shaft arms, whereby the same is actuated separately from the ring-rails, and, secondly, the adjustable connections between the side-rods of the said frame and the cross-bars, rods, or wires thereof whereby I provide for varying the distance apart of the side-rods and the direction of the cross-bars, rods, or wires, with respect to that of one of the side-rods. I have made claims in the said application, also, to the features of the forms of directive devices which are shown in Figs. 19, 20, 21, 22, and 23, the same comprising the guides provided with vertical surfaces whereby the separator-rails are prevented from moving transversely of the ring-frame, and, more particularly, the slotted brackets in which the separator-rails are fitted, and the collars on the separator-rails on opposite sides of the said brackets. These matters I do not claim specifically herein, nor do I lay claim broadly herein to the combination with the separators, the separator-rail, and a stop provided on one of the separators, or otherwise arranged to move in unison with the separator-rail, of a support constructed to permit the separator-rail to be unobstructedly removed therefrom before the separators have been turned out of their operative position, it having an open bearing from which the rail-journal may be removed

directly, and, on its front portion, a rest without obstruction to interfere with the stop while the rail is being removed. This combination I have claimed in my patent for improvements in separator-mechanisms for ring-spinning frames granted May 30, 1893, No. 498,338.

I claim as my invention—

1. The combination with the separators, the separator-rail, and the cross-shaft arm, of the vibratile connecting-rod carrying the separator-rail and swinging freely laterally in unison with the cross-shaft arm as it is raised and lowered by the latter, and directive means whereby to maintain the separators in proper position relative to the spindles, substantially as described.

2. The combination with the ring-rail, the lifting-rod, the separators, the separator-rail, and the cross-shaft arm acting to move the lifting-rod and thereby effect the traversing of the ring-rail and rings, of the vibratile connecting-rod carrying the separator-rail and swinging freely laterally in unison with the cross-shaft arm as it is raised and lowered by the latter, and directive means whereby to maintain the separators in proper position relative to the spindles, substantially as described.

3. The combination with the separators, the separator-rail, and the cross-shaft arm, of the vibratile connecting-rod carrying the separator-rail and swinging freely laterally in unison with the cross-shaft arm as it is raised and lowered by the latter, and directive means applied to the upper end of the connecting-rod whereby to maintain the separators in proper position relative to the spindles, substantially as described.

4. The combination with the ring-rail, the lifting-rod, the separators, the separator-rail, and the cross-shaft arm acting to move the lifting-rod and thereby effect the traversing of the ring-rail and rings, of the vibratile connecting-rod carrying the separator-rail and swinging freely laterally in unison with the cross-shaft arm as it is raised and lowered by the latter, and directive means applied to the upper end of the connecting-rod whereby to maintain the separators in proper position relative to the spindles, substantially as described.

5. The combination with the separators, the separator-rail, and the cross-shaft arm, of the vibratile connecting-rod carrying the separator-rail and swinging freely laterally in unison with the cross-shaft arm as it is raised and lowered by the latter, and an encircling guide applied to the upper end of the connecting-rod near to the separator-rail, substantially as described.

6. The combination with the separators, the separator-rail, and the cross-shaft arm, of the vibratile connecting-rod carrying the separator-rail and swinging freely laterally in unison with the cross-shaft arm as it is raised and lowered by the latter, and an encircling

guide applied to the upper end of the connecting-rod near to the separator-rail and having a tapering hole therethrough, substantially as described.

5 7. The combination with the separators, the separator-rail, and the cross-shaft arm, of the vibratile connecting-rod carrying the separator-rail and swinging freely laterally in unison with the cross-shaft arm as it is raised 10 and lowered by the latter, an encircling guide applied to the upper end of the connecting-rod near to the separator-rail, and a stand on which said guide is mounted, having means for securing the said guide in the desired position of vertical adjustment, substantially as described.

8. The combination with the separators, the separator-rail, and the cross-shaft arm, of the vibratile connecting-rod carrying the separator-rail and swinging freely laterally in unison with the cross-shaft arm as it is raised 20 and lowered by the latter, an encircling guide applied to the upper end of the connecting-rod near to the separator-rail, and means for 25 supporting the said guide and securing it in the desired position of horizontal adjustment, substantially as described.

9. The combination with the separators, the separator-rail, and the cross-shaft arm, of the vibratile connecting-rod carrying the separator-rail and swinging freely laterally in unison with the cross-shaft arm as it is raised 30 and lowered by the latter, an encircling guide applied to the upper end of the connecting-rod near to the separator-rail, a stand having means for securing the said guide in the desired position of vertical adjustment, and means for securing the said guide to the stand 35 with capacity for horizontal adjustment, substantially as described.

10. The combination with the ring-rails on the opposite sides of a ring-frame, and means for operating the same, of the separator-rails on the said opposite sides, the separators carried thereby, independent actuating connections whereby the separator-rails are operated, and a cross-bar or wire spacing apart the said separator-rails at a fixed distance, substantially as described.

11. The combination with the separator-rails on the opposite sides of a ring-frame, the separators carried thereby, and rods sustaining the said separator-rails, of a cross-bar or wire uniting the devices on opposite sides 55 of the ring-frame, and means for reciprocating said rods vertically, substantially as described.

12. The combination with the separator-rails on the opposite sides of a ring-frame, the separators carried thereby, rods sustaining the said separator-rails, and means for reciprocating the said rods vertically, of a cross-bar or wire uniting the corresponding rods on opposite sides of the ring-frame, substantially 65 as described.

13. The combination with the separator-rails on the opposite sides of a ring-frame, the

separators carried thereby, rods sustaining the said separator-rails, and means for reciprocating the said rods vertically, of a cross-bar or wire uniting the corresponding rods on opposite sides of the ring-frame, and means for adjusting the distance apart of the said rods, substantially as described.

14. The combination with the separator-rails on the opposite sides of a ring-frame, the separators carried thereby, rods sustaining the said separator-rails, and means for reciprocating the said rods vertically, of a cross-bar or wire, and clamps connecting the opposite 80 ends of said cross-bar or wire with the corresponding rods on opposite sides of the ring-frame, substantially as described.

15. The combination with the separator-rails on the opposite sides of a ring-frame, the separators carried thereby, rods sustaining the said separator-rails, and means for reciprocating the said rods vertically, of a cross-bar or wire having loops or eyes at the ends thereof, and clamps connecting the opposite 90 ends of said cross-bar or wire with the rods, each clamp formed in two slotted halves or sections fitting the corresponding sustaining rod and one end of the cross-bar or wire, and being provided with a securing bolt which 95 passes through the slots and the eye or loop at the corresponding end of the cross-bar or wire, and also with a nut fitted to the threaded end of the bolt, substantially as described.

16. The combination with a rod, and a wire 100 or bar having an eye or loop at the end thereof, of a clamp uniting the same, consisting of the two halves or sections 3711, 3711, slotted at 3715, 3715, and formed with the concave portions 3712, 3712, fitting the rod and 105 the notches 3714, 3714, fitting the wire or bar, a bolt passed through the slots and the eye or loop, and a nut on the threaded end of the bolt, substantially as described.

17. The combination with the separator-rails on the opposite sides of a ring-frame, the separators carried thereby, rods sustaining the said separator-rails, means for reciprocating the said rods vertically, and a cross-bar or wire uniting the corresponding rods on 115 opposite sides of the ring-frame, of directive means whereby to maintain the separators in proper position relative to the spindles, substantially as described.

18. The combination with the separator-rails on the opposite sides of a ring-frame, the separators carried thereby, rods sustaining the said separator-rails, means for reciprocating the said rods vertically, and a cross-bar or wire uniting the corresponding rods 125 on opposite sides of the ring-frame, of directive means for preventing movement of the separator-rails transversely of the ring-frame, substantially as described.

19. The combination with the separator-rails on the opposite sides of a ring-frame, the separators carried thereby, rods sustaining the said separator-rails, means for reciprocating the said rods vertically, and a cross-

bar or wire uniting the corresponding rods on opposite sides of the ring-frame, of directive means for preventing movement of the separator-rails longitudinally of the ring-frame, substantially as described.

20. The combination with the separator-rails on the opposite sides of a ring-frame, the separators carried thereby, the cross-shafts, the cross-shaft arms, and vibratile connecting rods sustaining the said separator-rails and actuated by the said cross-shaft arms, of a cross-bar or wire uniting the corresponding rods on opposite sides of the ring-frame, and directive means whereby the separator-rails are restrained from improperly moving in the ring-frame, substantially as described.

21. The combination with the separator-rails on the opposite sides of a ring-frame, the separators carried thereby, the cross-shafts, the cross-shaft arms, and vibratile connecting-rods sustaining the said separator-rails and actuated by the said cross-shaft arms, of a cross-bar or wire uniting the corresponding rods on opposite sides of the ring-frame, and directive means applied to one of such rods for preventing movement of the separator-rails transversely of the ring-frame, substantially as described.

22. The combination with the separator-rails on the opposite sides of a ring-frame, the separators carried thereby, the cross-shafts, the cross-shaft arms, and vibratile connecting-rods sustaining the said separator-rails and actuated by the said cross-shaft arms, of a cross-rod or wire uniting the corresponding rods on opposite sides of the ring-frame, and a guide encircling one of such connecting-rods for determining the path of motion of the separator-rails, substantially as described.

23. The combination with the machine-framing, the spindle and guide-rails, the spindles, the ring-rail and the separator-rail both actuated from the cross-shaft arm, and the cross-shaft arm, of means for supporting the cross-shaft which permit changes of height of the spindle-rail without changes of height of the cross-shaft, substantially as described.

24. The combination with the machine-framing, the spindle and guide-rails, the spindles, the ring-rail, the separator-rail, the lifting-rod, a rod for operating the separator-rail, and the cross-shaft arm acting through the said rods to communicate traversing movements to the ring-rail and the separator-rail, of the supplemental rail carrying the bearings for the cross-shaft and having separate attachment to the machine-framing, substantially as described.

25. The combination with the separators, the separator-rail having a stop which is carried thereby and moves therewith, a vertically-movable supporting-rod, and means for actuating said supporting-rod, of a support having an open bearing for the journal or pivot of the separator-rail and also having at the front thereof a rest with which the said stop engages at a point to the front of the separator-rail and in advance of the center of gravity of the combined separators and separator-rail, substantially as described.

26. The combination with the separators, the separator-rail having a stop which is carried thereby and moves therewith, a vertically-movable supporting-rod, and means for actuating said supporting-rod, of a support carried by said supporting-rod and having an open bearing for the journal or pivot of the separator-rail and also having at the front thereof a rest with which the said stop engages at a point to the front of the separator-rail and in advance of the center of gravity of the combined separators and separator-rail, the said bearing and rest being without obstruction thereabove to interfere with the removal of the separator-rail from the support at any time before the separators have been turned out of their operative positions, substantially as described.

In testimony whereof I affix my signature in the presence of two witnesses.

CHANNING WHITAKER.
